Edward Pitcher, Inventor:
By Atkins & Atkins, Attorneys.

UNITED STATES PATENT OFFICE.

EDWARD RITCHIE, OF ASTORIA, OREGON, ASSIGNOR TO SELF CLEARING ANCHOR COMPANY, A CORPORATION OF OREGON.

ANCHOR.

Application filed July 19, 1921. Serial No. 485,912.

To all whom it may concern:

Be it known that I, EDWARD RITCHIE, a citizen of the United States of America, and resident of Astoria, in the county of Clatsop, 5 in the State of Oregon, have invented certain new and useful Improvements in Anchors, of which the following is a specification, reference being had to the accompanying drawings.

10 My invention relates to marine anchors and has for its objects the production of such an anchor that possesses increased efficiency in proportion to weight over anchors heretofore devised; which has improved 15 means for insuring its holding effect and for tripping the anchor; and which is designed and adapted, when raised, to hang true and snug against the ship's side wherever it is designed to be hung.

20 What constitutes my invention will be hereinafter specified in detail and succinctly set forth in the appended claims.

In the accompanying drawings,

25 Figure I is a side elevation of my anchor showing its parts in the pendent position in full lines, and showing in dotted lines the draw-bar swung to one side.

30 Figure II is a view similar to Figure I, except that in Figure II the latch of the draw-bar is shown in full lines in the latched position and in dotted lines in the unlatched position preparatory to tripping the anchor.

35 Figure III is a view corresponding to that shown in full lines in Figure I, but at right angles to that figure.

40 Referring to the numerals on the drawings: 1 and 2 indicate the two sides of the shank of my anchor which is preferably made of one piece and bifurcated so as to define said sides, from toe 3 to crown 4. At the open end of the shank near the crown 4 the sides 1 and 2 are securely united, preferably by a cylindrical cross-piece 5 which constitutes a fixed shaft for the pivotal accommodation upon it, between the sides 1 and 2, of a trunnion-head 7, which is perforated by an oblong slot 8, that is disposed in longitudinal alignment with the longitudinal axis of a rotative draw-bar 9 of which the trunnion-head 7 forms one end. The width of the draw-bar 9 is sufficiently less than that of the distance between the sides 1 and 2 to permit free oscillation or even rotatory movement of the draw-bar in 55 the space between the sides.

For the free accommodation of the movement of the trunnion-head rotatively about the cross-piece 5, I provide an enlarged recess 10 that is defined on opposite sides by oppositely curved flanges 11 and 12. There are two flanges 11 which project from the respective sides 1 and 2, one towards the other. In like manner the flanges 12 are oppositely disposed upon the respective side-pieces 1 and 2, the flanges 11 and 12 being arranged in longitudinal disposition in respect to the draw-bar 9. The external and the internal or opposing contours of the respective pairs of flanges 11 and 12 are defined by coaxial curved faces 15 and 16, and 17 and 18, respectively. Against the opposing faces 15 and 17, the trunnion-head 7 bears, alternately, according to the position in the slot occupied by the cross-piece 5. The location of the faces 17 is nearer the crown 4 and that of the faces 15 is the more remote therefrom, and their respective functions are distinct. The function of the faces 17 is to afford a bearing for the trunnion-head 7 and so to relieve the cross-piece 5 of the weight of the anchor when it is sustained by the draw-bar 9, as hereinafter explained. The function of the faces 15 is to afford a guide-stop to the trunnion-head when tension upon the draw-bar pulls the trunnion head in a direction away from the faces 17.

45 The thickness of the draw-bar 9 is reduced, as indicated at 20, to accommodate the presence of the flanges 11 and 12 to the free movement, longitudinally and rotatively, of the draw-bar between them. The longitudinal extent of said reduction of thickness of the draw-bar is defined at one end by the trunnion-head 7 and, at the other end, by snubs 21 and 22 disposed respectively upon opposite sides of the draw-bar.

50 The presence of the external curved faces 16 and 18 is to accommodate the presence of the snubs 21 and 22 to the relative movement of the draw-bar 9 about the cross-piece 5; but the faces 16 have the distinct function of cams in guiding the snubs 21 and 22 towards medial cams 23 and 24 provided upon the flanges 11, respectively, as often as the draw-bar 9 is swung from either side into the space between the side-pieces 1 and 2. The effect of the action of the snubs 21 and 22 against the medial cams 23 and 24 is to impart a thrust movement to the draw-bar 9 in the direction of its longi-

tudinal axis. The purpose of said thrust movement is to drive the free end of the draw-bar that terminates in a latch 25 into operative engagement with a keeper 27 formed on the inside of the toe 3, and that engagement is maintained so long as cooperation of the snubs 21 and 22 and the medial cams 23 and 24 continues.

The latch end of the draw-bar 9 is provided with a shackle 28, of any suitable and preferred form, as means for attachment of a cable 30 to the anchor; and the operation of the anchor and of the draw-bar is dependent upon such attachment, in the manner to be presently described.

The anchor head comprises four flukes 31, of which two are disposed upon opposite sides of each of the side-pieces 1 and 2. They have, in effect, the gripping action upon the ground of the mushroom type of anchor, but are distinguished therefrom in form and function by having each pair separated by toppling ends 32 and 33, each of which is preferably of semi-circular outward contour.

Each fluke is preferably claw-shaped and defined by an external curved face 34 which takes into the ground and grips it tenaciously until the shank 1-2 is lifted to the tripping position. The curved face 34 serves the further function of facilitating the presentation of the flukes of the anchor in operative gripping position. Tension on the draw-bar 9 operates to throw the anchor over into such position if, on lowering, the shank 1-2 of the anchor should extend in the opposite direction from that of the draw-bar. The office of the toppling ends 32 and 33 is to insure, in every presentation of the anchor against the ground, the throwing of the anchor upon one or the other of its sides, in which position oblique tension upon the cable 30 is certain to effect engagement of the flukes with the ground.

I prefer to provide upon opposite sides of the crown 4 fins 35 upon the bottoms of the toppling ends 32, and 33, respectively. Besides stiffening and weighting said toppling ends, they define, upon their opposite sides, pockets 36 which will, by gathering sand, afford a temporary make-weight to the anchor that will tend to hold it to its work.

I prefer, also, to provide upon the trunnion head, diametrically opposite the draw-bar 9, a lifting-lever 37 which will, by tension applied to the draw-bar through the cable 30, exert a lifting force against the ground to pry the anchor loose, whenever it is desired to trip the anchor preparatory to raising it.

The operation of my anchor in service may be briefly described as follows.

When not in use it is suspended, as shown in Figure I, by the draw-bar 9 from the cable 30 attached to the shackle 28, and hangs

snugly, as against the ship's side, from any usual or preferred point of suspension.

When dropped, the anchor meets the ground, it may be assumed, in any conceivable manner of presentation. Be the point of presentation what it may, the anchor will ultimately, by reason of its shape and under tension upon the cable 30, assume a position in which it is supported on one side by the flukes 31 on that side and by the toe 3, the cable being disposed so as to pull the draw-bar 9 towards the toe, as shown in Figure II. In that position, if the shank 1-2 be located beneath the draw-bar relaxation of tension upon the cable 30 will permit the weight of the draw-bar 9 to compel it to fall into the space between the shank side-pieces 1 and 2. That drop into place of the draw-bar will, in consequence of cooperation of the medial cams 23 and 24 with the snubs 21 and 22, impart end-thrust to the draw-bar and compel engagement of its latch 25 with the keeper 27. If the draw-bar 9 is beneath the shank 1-2 tension thereon operates through the flukes of the anchor to depress the shank with a holding or latching effect against the upward pull of the draw-bar. Afterwards all tension upon the cable in a direction oblique to the vertical and from the cross-piece 5 will be communicated to the anchor to force it with holding effect against the ground, as may be better understood upon reference to Figure II.

In order to trip the anchor, pull upon the cable is made, in the usual manner, tending to bring it into vertical alignment with the shackle 28, as shown in dotted lines in Figure II. The effect if the draw-bar 9 is held by the keeper 27 is to force the round end of the latch 25 against the curved face of the keeper 27, and thereby to free the draw-bar 9, whose retreating movement is permitted by slip of the walls of the slot 8 upon the cross-piece 5. Thereupon, continued lift of the draw-bar imparts movement to the lifting lever 37, with the functioning effect thereof already specified to facilitate the loosening of the anchor from the ground in the operation of tripping it. If the draw-bar and shank are held with latch effect by oppositely acting forces and not by the keeper 27, the tripping is effected in like manner but without the necessity of extricating the bar 9 from the keeper 27.

When the anchor is lifted free of the ground, it will fall, by action of gravity, into the position shown in Figure I, which is the position first above referred to in the foregoing description of operation.

What I claim is:

1. An anchor comprising an integral bifurcated shank, toe piece, and lateral flukes, combined with a draw-bar movably and pivotally attached to the shank and means for compelling presentation of the flukes to

the ground under tension exerted upon the draw-bar.

2. In an anchor of the kind described, the combination with a bifurcated shank, and cross-piece uniting the sides of the shank near its open end, of a draw-bar provided with a slot for reception of said cross-piece, oppositely acting members upon the shank and draw-bar adapted to impart end-thrust to the draw-bar under impulse of swing of the draw-bar, said members cooperating with mechanism provided for latching the draw-bar to the shank under tension on the draw-bar in one direction and for releasing them under contrary tension.

3. In an anchor, the combination with a bifurcated shank having a toe, sides and flukes thereon, and a cross-piece uniting the sides of the shank near its open end, of a draw-bar provided with a longitudinally slotted trunnion-head upon the cross-piece, opposite curved flanges upon the shank sides for the accommodation of the trunnion-head, a latch on the free end of the draw-bar, a keeper on the toe, medial cams upon one pair of the curved flanges, respectively, and snubs upon opposite sides of the draw-bar for operative engagement with said cams, all cooperative substantially as set forth.

30 4. An anchor comprising an integral bifurcated shank, toe piece, and lateral flukes,

combined with a draw-bar movably attached to the shank with latching effect, a longitudinally slotted trunnion head upon the draw-bar and means for compelling presentation of the flukes to the ground under tension exerted upon the draw-bar, said means comprising curved toppling ends, and external curved faces on the flukes, respectively, substantially as described.

35

5. An anchor comprising an integral bifurcated shank, toe piece, and lateral flukes, combined with a draw-bar movably attached to the shank with latching effect, a longitudinally slotted trunnion-head upon the draw-bar and means for compelling presentation of the flukes to the ground under tension exerted upon the draw-bar, said means comprising curved toppling ends, substantially as described, pocket-defining fins upon the bottoms of the respective toppling ends 50 and external curved faces in the flukes.

40

6. In an anchor of the kind described, the combination with its bifurcated shank, and flukes upon opposite sides thereof, of a draw-bar pivotally mounted between the sides of the shank and a lifting lever carried by the draw-bar upon the opposite side of its pivotal support.

45

In testimony whereof, I have hereunto set my hand.

55

EDWARD RITCHIE.
